FIG. 3

FIG. 1

FIG. 2

FIG. 1 is a top plan view of a cribbage board showing my design.

FIG. 2 is a side elevational view thereof.

FIG. 3 is a cross sectional view substantially along the line 3—3 of FIG. 1.

For a convenience of illustration, the apertures in FIG. 1 are shown as circular spots.

The elevation of the four sides is similar and the underside plan view is planar.

I claim:

The ornamental design for a cribbage board, as shown and described.
